UNITED STATES PATENT OFFICE.

ADOLPH J. IWAN, OF MARSHFIELD, WISCONSIN.

DESIGN FOR A POISON-BOTTLE.

No. 39,777.

Specification for Design.

Patented Jan. 19, 1909.

Application filed November 7, 1908. Serial No. 461,589. Term of patent 14 years.

To all whom it may concern:

Be it known that I, ADOLPH J. IWAN, a citizen of the United States, residing at Marshfield, in the county of Wood and State of Wisconsin, have invented a new, original, and ornamental Design for Poison-Bottles, of which the following is a specification.

I claim:—

The ornamental design for a poison bottle, as shown.

In testimony whereof I affix my signature in presence of two witnesses.

ADOLPH J. IWAN.
